US00D993394S

(12) **United States Design Patent** (10) **Patent No.:** **US D993,394 S**
(45) **Date of Patent:** **** Jul. 25, 2023**

(54) **SURGICAL MASK**

(71) Applicant: **REVOLUTIONARY MEDICAL DEVICES, INC.**, Mettawa, IL (US)

(72) Inventors: **Thomas M. Reilly**, Tucson, AZ (US); **Michael J. Pedro**, Brooklyn, NY (US); **Steven H. Cataldo**, New York, NY (US); **Ryan G. Redford**, Tucson, AZ (US); **David M. Kane**, Tucson, AZ (US)

(73) Assignee: **SUNMED GROUP HOLDINGS, LLC**, Grand Rapids, MI (US)

(**) Term: **15 Years**

(21) Appl. No.: **29/861,714**

(22) Filed: **Dec. 1, 2022**

Related U.S. Application Data

(63) Continuation of application No. 29/702,204, filed on Aug. 16, 2019, now Pat. No. Des. 976,393, which is a continuation of application No. 29/657,380, filed on Jul. 20, 2018, now Pat. No. Des. 862,687, which is a continuation of application No. 29/530,124, filed on Jun. 12, 2015, now Pat. No. Des. 825,740, which is a continuation-in-part of application No. 29/520,420, filed on Mar. 13, 2015, now abandoned, which is a (Continued)

(57) **CLAIM**

The ornamental design for a surgical mask, as shown and described.

DESCRIPTION

FIG. 1 is a front plan view of the surgical mask in accordance with our invention;

FIG. 2 is a right side elevation view thereof;

FIG. 3 is a left side elevation view thereof;

FIG. 4 is right side perspective view of the mask thereof, separated in two parts;

FIG. 5 is a right side perspective view thereof; and,

FIG. 6 is a bottom perspective view of the surgical mask. The broken lines in the drawings illustrate portions of the surgical mask that form no part of the claimed design.

1 Claim, 6 Drawing Sheets

Related U.S. Application Data

continuation-in-part of application No. 29/511,716, filed on Dec. 12, 2014, now abandoned.
